UNITED STATES PATENT OFFICE

2,453,467

PICTURE HANGER

Thomas F. Smith, Pasadena, Calif.

Application September 28, 1945, Serial No. 619,066

3 Claims. (Cl. 248—28)

1

The present invention relates to new and useful improvements in picture hangers, and has for its primary object to provide means for supporting a picture out of contact with a wall to which the hanger is attached, and also for supporting the picture in a freely swingable position to cause gravitation of the picture in a true perpendicular position.

A further object of the invention is to provide a hanger of this character by means of which the picture may be removed from the hanger without removing the hanger from the wall.

A still further object of the invention is to provide a device of this character of simple and practical construction, which is strong and durable, neat and attractive in appearance, efficient and reliable in use and otherwise well adapted for the purposes for which the same is intended.

Other objects and advantages reside in the details of construction and operation, as more fully hereinafter described and claimed, reference being had to the accompanying drawing forming part hereof, wherein like numerals refer to like parts throughout, and in which:

Figure 1 is a side elevational view.

Figure 2 is a front elevational view.

Figure 3 is a vertical sectional view.

Figure 4 is a fragmentary sectional view taken substantially on a line 4—4 of Figure 1.

Figure 5 is a plan view showing the blank of strap metal from which the hanger is constructed.

Referring now to the drawing in detail, wherein for the purpose of illustration I have disclosed a preferred embodiment of the invention, the numeral 5 designates the hanger generally which is constructed of a strip of strap metal of the form as illustrated in Figure 5 of the drawing and bent upwardly at one end along a transverse line indicated at 6 to provide a wall bracket having a vertical attaching backing strip 7 and a forwardly and upwardly projecting arm 8.

A tongue 9 is struck from the upper portion of the attaching strip 7 and is bent horizontally forwardly and formed at its outer end with a downturned lip 10. At the intersection of the lip 10 with the tongue 9 an opening 11 is provided through which a nail or similar fastening device 12 is inserted at a downwardly inclined angle through an opening 13 in the upper portion of the backing strip 7 for driving into a wall or other supporting structure 14.

The portion of the upper end of the attaching strip 7 from which the tongue 9 is struck is bent downwardly below the tongue against the front

2

surface of the attaching strip 7, as indicated in Figures 1 and 3 of the drawing, and is then bent forwardly and downwardly to form a bearing 15 spaced forwardly of the attaching strip 7 and formed at its lower edge with a slot 16 in which the rear end of a screw 17 is engaged.

The upper end of the arm 8 is also formed with a slot 18 in which the screw 17 is supported at its forward portion.

10 The screw 17 is preferably constructed of a headless type and is provided at its intermediate portion with a plastic or other suitable body 19 in which the screw is embedded.

In the operation of the device, the threaded end of the screw 17 is threaded into the back of the top of a picture frame 20 at the center thereof and the attaching strip 7 of the hanger then secured in a desired position to the wall by means of the nail 12.

15 The screw 17 is then tilted so as to engage the rear end of the screw in the slot 16 of the bearing 15 and the front portion of the screw is then seated in the slot 18 of the arm 8, the screw thus being supported for free pivotal movement

20 in the bearing 15 and arm 8 and the picture 20 is supported at the front end of the screw in spaced relation outwardly from the wall 14 in the manner as illustrated in Figure 1 of the drawing.

25 The lower end of the picture will then gravitate in the action of a pendulum to support the picture in a true perpendicular position.

30 It is believed that the details of construction, manner of use and advantages of the device will be readily understood from the foregoing without further detailed explanation.

35 It is to be understood, however, that even though I have herein shown and described a preferred embodiment of my invention, the same is susceptible of certain changes fully comprehended by the spirit of the invention as herein described, and the scope of the appended claims.

Having thus described the invention, what I claim is:

40 1. In a hanger for picture frames and the like, a bracket having a backing strip adapted for attaching to a wall or the like, said backing strip having a receiving socket therein, and also having an arm extending outward from the lower end thereof with an open socket thereon aligned with the socket in the backing strip, a screw adapted for mounting in a picture frame with the axis thereof perpendicular to the surface of the frame, said screw having an enlargement thereon for positioning between the receiving

and open sockets of the bracket with the screw freely held in said sockets.

2. In a hanger for picture frames and the like, comprising the combination of a wall bracket adapted to be supported on the face of a wall, and a screw adapted for attaching to the picture frame with said screw extending perpendicularly from the frame, said bracket having oppositely positioned receiving sockets for holding said screw, and means on said screw positioned intermediate of said sockets with the screw in the sockets restraining said screw from accidental separation thereof from the bracket by outward sliding thereof.

3. A hanger for picture frames and the like, comprising, the combination of a wall bracket adapted to be supported on the face of the wall, and a screw adapted for attaching to the picture frame with the said screw extending perpendicular from the frame, said bracket having inclined nail receiving sockets for attachment thereof to a wall, an inner screw receiving socket, and a diagonal outwardly projecting arm with a screw

receiving socket at the upper end and aligned with said inner screw receiving socket, and an enlargement on said screw adapted for positioning between said sockets with the screw freely held in the sockets restraining said screw from accidental separation thereof from said socket by outward sliding movement thereof.

THOMAS F. SMITH.
